UNITED STATES PATENT OFFICE.

JAMES G. MACLAREN, OF HARRISON, NEW YORK, ASSIGNOR TO THE LAMSON COMPANY, OF NEWARK, NEW JERSEY, A CORPORATION OF NEW JERSEY.

PNEUMATIC-DESPATCH-TUBE APPARATUS.

1,133,812.

Specification of Letters Patent. Patented Mar. 30, 1915.

Application filed August 20, 1908. Serial No. 449,562.

To all whom it may concern:

Be it known that I, JAMES G. MACLAREN, of Harrison, in the county of Westchester and State of New York, have invented certain new and useful Improvements in Pneumatic-Despatch-Tube Apparatus, of which the following is a specification.

My invention relates to improvements in pneumatic despatch tube apparatus and particularly to that class wherein a normally closed air-valve is located in the suction-tube connecting the transmission tubes with the usual vacuum drum and which valve is adapted to control and limit the flow of air through the transmission tubes to the interval necessary for the transmission of the carriers.

The object of my invention is to provide means independent of the vacuum in the system for operating said valve, whereby the same is controlled from either of the stations along the line to create and time the flow of air through the transmission tubes for driving carriers therethrough. This is accomplished by providing a supply of compressed air generated by an independent pump which is connected with the mechanism for operating the air-valve and also connected with and controlled by a device located at each of the stations along the line which will be hereinafter fully described.

In the accompanying drawings which illustrate a construction embodying my invention, Figure 1 is a diagrammatic view showing the operating mechanism in section and with parts in normal position and connected with a circuit of pneumatic transmission tubes. Fig. 2 is an enlarged sectional view showing the controlling mechanism in normal position, connected with and operated by the despatching inlet at a sub-station. Fig. 3 is an enlarged sectional view showing the normal position of the controlling device located at the bell-mouth or central station. Fig. 4 is an enlarged sectional view of the time-controlled mechanism for operating the air-valve, the full lines representing the normal or non-operating position of the same while the dotted lines represent the open or operating positions. Fig. 5 is an enlarged sectional view of the relief valve connected with the supply of compressed air.

Like characters of reference refer to like parts throughout the several views.

Referring to Fig. 1, the transmission tube 1 connects the central station C with the discharge terminal 3 controlled by the usual delivery valve 4, located at the sub-station S. 5 is a return tube connecting the terminal 3 at the sub-station S with the discharge terminal 7 controlled by the usual valve 8 located at the central station C. 9 is a tube connecting the terminal 7 with the ordinary vacuum drum 11, in which a vacuum is maintained by air exhauster of lever 12 operated by an electric motor 13 through belt 14. 6 is the ordinary despatching inlet for inserting carriers into the transit tube 5 at sub-station S and 2 is the bell-mouth or air inlet for inserting carriers into transit tube 1 at the central station C. Interposed in the tube 9 is a casing 10, having two chambers 47 and 54, connected by a port 48^a 75 which is normally closed by a valve 48 secured to one end of a valve stem 49 mounted in a bearing in said casing 10. The opposite end of the valve stem 49 is attached to a diaphragm 50 mounted in the outer 80 part of the casing 10 and which is held in the full-line position shown in Fig. 4 by a suitable spring 53. 56 is a by-pass connecting the chamber 52 on one side of said diaphragm with the chamber 51 on the opposite side and 57 is a timing screw adapted to be adjusted to restrict said by-pass 56, if necessary. 55 is a passage connecting the chamber 52 with the vacuum in the chamber 47. The chamber 51 is connected through 90 pipes 34 and 33 with the chamber 29 in a casting 27, mounted on the tube 1 adjacent to the bell-mouth 2. 29^a is a port normally closed by a valve 30 and adapted to admit compressed air from the chamber 28 into the 95 chamber 29 when said valve is opened. 31 is a shaft to which the valve 30 is secured and 32 is a trip fixed to said shaft 31 at one end, the free end of said trip projecting into the tube 1 adjacent to bell-mouth 2. 26 is a 100 pipe connecting the chamber 28 with the compressed air reservoir 18 air being supplied through a pipe 16 connected with a suitable air pump 15 operated by a crank 12^a secured to the shaft of the blower 12. 105 17 is a check valve for holding the compressed air in reservoir 18. 25 is relief valve interposed in the pipe 16 between the check

valve 17 and the pump 15. This valve consists of the casing 25 in which is mounted a valve 23 connected at one end with the valve stem 22 and normally closing the inner side of casing 25 from the atmosphere. The opposite end of the stem 22 is connected with the diaphragm 21 mounted in casing 20, said diaphragm being of greater area than the valve 23 and exposed on its inner side to the pressure in reservoir 18, communicated through pipe 19. 24 is a spring adapted to counter-balance the normal or required pressure in the reservoir 18, which acts on diaphragm 21 and tends to open the valve 23 to relieve the air-supply from the pump 15 to the atmosphere when the pressure in reservoir 18 rises above normal. The chamber 51 is connected through pipes 34 and 36 with chamber 40 in the casing 38 mounted on tube 5 adjacent to the despatching inlet 6 at sub-station S. 37 is a pipe connecting the reservoir 18 with chamber 39 in said casing 38 and 41 is a valve pivoted at 42 and normally closing port 40^a which is adapted to connect chambers 39 and 40. The handle 45 to which the valve 6 is secured is pivoted at 46 and connected through a link 44 with one end of lever 43 upon which valve 41 is mounted.

30 The operation of the device is as follows:—In despatching a carrier from central station C to sub-station S, the operator inserts the carrier into the bell-mouth 2 where it engages and depresses the trip 32 opening valve 30, admitting compressed air from the chamber 28 into chamber 29 thence through pipes 33 and 34 to chamber 51 causing the diaphragm 50 to be forced over against the tension of spring 53 to the dotted line position shown in Fig. 4, opening valve 48 causing a flow of air through bell-mouth 2, transit tubes 1 and 5 thence through tube 9 by way of chamber 54 and 47 to the vacuum drum 11. The carrier is 40 now driven through tube 1 toward sub-station S and immediately after passing over trip 32 the valve 30 is closed by the pressure in chamber 28 cutting off the supply of compressed air to chamber 51. The 50 vacuum now acting through passage 55, chamber 52 and by-pass 56, gradually exhausts the air from chamber 51, allowing the spring 53 to slowly move the diaphragm 50 and valve 48 until by the time the carrier 55 has delivered at sub-station S the valve 48 has entirely closed cutting off the flow of air. The timing valve 57 may be adjusted to properly time the closure of valve 48. In despatching a carrier from sub-station 60 S to central station C the operator opens the despatching inlet 16, inserts the carrier and closes said inlet. The opening of said inlet operates through link 44 and lever 43 to open the valve 40 admitting compressed air from chamber 39 into chamber 65

40, thence through pipes 36 and 34 to chamber 51 opening the valve 48 as heretofore described, causing a flow of air through the bell-mouth 2, driving the carrier toward the central station C. The closure of the 70 inlet 6 closes the valve 41 cutting off the supply of compressed air to chamber 51. The air in said chamber 51 is gradually exhausted and the valve 48 closed in the manner hereinbefore described cutting off the 75 flow of air by the time the carrier has delivered at the central station C.

Having thus described my invention and set forth a construction embodying the same, what I claim as new and desire to secure by 80 Letters Patent of the United State is:

1. In a pneumatic despatch tube apparatus, a tube for the transmission of carriers, means for exhausting air from said tube, a normally closed air valve for controlling the 85 flow of air through said tube, a source of compressed air, mechanism to be operated upon the despatching of a carrier to cause said compressed air to open said valve, and a connection between said mechanism and 90 air exhausting means, said apparatus having provisions for timing the closure of said valve after it has been so opened by permitting a regulated flow of compressed air from said mechanism through said connec- 95 tion to said air exhausting means.

2. In a pneumatic despatch apparatus, the combination of a transmission tube having a carrier despatching part provided with a closure, means for producing a carrier propelling flow of air adapted to be placed in communication with said tube, a valve controlling said communication, a fluid pressure operated device for actuating said valve, a valve chamber adjacent said closure, an auxiliary valve in said chamber, connections between said closure and said auxiliary valve whereby an actuation of said closure causes an actuation of said auxiliary valve, two auxiliary conduits leading to said valve chamber, one of said auxiliary conduits being in communication with one side of said auxiliary valve and the other being in communication with the other side of said auxiliary valve, and a source of compressed air in connection with one of said auxiliary conduits, the other of said auxiliary conduits being connected to said fluid pressure operated device. 110

3. In a pneumatic despatch apparatus, 120 the combination of a transmission tube having a carrier despatching part, means for producing a carrier propelling flow of air adapted to be placed in communication with said tube, a valve controlling said communication, a fluid pressure operated device for actuating said valve, a valve chamber having therein an auxiliary valve, means for controlling said auxiliary valve from a point adjacent said carrier despatching 125 130

part, two auxiliary conduits, one of which is in communication with one side of said auxiliary valve and extends thence to said pressure operated device, and a source of pressure fluid, the other of said auxiliary conduits extending from said pressure fluid source and communicating with the other side of said auxiliary valve.

In testimony whereof, I have signed my 10 name to this specification in the presence of two subscribing witnesses, this fifteenth day of August A. D. 1908.

JAMES G. MACLAREN.
